UNITED STATES PATENT OFFICE.

CHARLES M. HORTON, OF ELIZABETH, NEW JERSEY, ASSIGNOR TO THE SINGER
MANUFACTURING COMPANY, A CORPORATION OF NEW JERSEY.

TABI-FASTENER ATTACHMENT FOR SEWING-MACHINES.

958,251.

Specification of Letters Patent. Patented May 17, 1910.

Application filed January 24, 1910. Serial No. 539,686.

To all whom it may concern:

Be it known that I, CHARLES M. HORTON, a citizen of the United States, residing at Elizabeth, in the county of Union and State 5 of New Jersey, have invented certain new and useful Improvements in Tabi-Fastener Attachments for Sewing-Machines, of which the following is a specification, reference being had therein to the accompanying drawings.

This invention relates to an improvement in means for uniting the overlapped marginal portions of two pieces of fabric with interposed metal plates arranged at intervals 15 along the seam, as in the manufacture of that class of Japanese foot wear known as tabi, in which the two overlapping plies of the heel portion embrace between them one end of a fastening plate or fastener adapted 20 to engage a suitable fastening loop upon the other heel flap or portion of the article.

According to the present invention, the sewing machine bed-plate has preferably set into its upper face at the end adjacent the 25 stitch-forming mechanism the foot-piece of a forwardly extending bracket having upwardly projecting lugs entered by fulcrum pins carried by a rocking frame upon which is rigidly mounted an upright open-mouthed 30 chute to receive the fasteners and a rotary carrier formed with peripheral radially disposed recesses adapted to successively convey the fasteners from the mouth of the chute to the stitch-forming mechanism, the 35 fasteners being maintained in their respective recesses in the carrier by a runway mounted upon the rocking frame and embracing the marginal portion of the carrier between the mouth of the chute and the 40 stitching position. The feeding-mechanism comprises a feed-dog whose operative serrated work-engaging surface is substantially covered by the spring-actuated presser-foot in conjunction with a portion of the margin 45 of the rotary carrier, whereby the feed-dog acts not only to advance the overlapped plies of material beneath the presser-foot and upon opposite faces of the rotary carrier but serves to propel the latter in conveying the 50 fasteners from the chute or magazine to stitching-position.

The invention will be understood by reference to the accompanying drawings, in which—

55 Figure 1 is an elevation of the forward

portion of a sewing machine, partly in section, with a fastener feeding attachment applied thereto, and Fig. 2 is a plan of the same with the parts of the sewing machine above the work-plate omitted. Fig. 3 is a 60 front end view of the parts represented in Fig. 1. Fig. 4 is a perspective view of the rotary carrier disk and a portion of the frame upon which it is mounted, and Fig. 5 a detail perspective view of the cap-plate of 65 the runway. Fig. 6 is a side elevation and Fig. 7 a plan of the presser-foot. Fig. 8 is a perspective view of two overlapped pieces of fabric showing a line of stitching by which they are united together with interposed 70 fasteners and Fig. 9 a similar view showing the united plies of fabric reversed to expose the operative portions of the fasteners.

The machine frame is formed with the bed-plate 1 and overhanging bracket-arm provided with the head 2 in which is mounted the reciprocating needle-bar 3 carrying the needle 4 and the presser-bar 5 embraced by the pressure-spring 6 and having secured to its lower end by means of the fastening 80 screw 7 the presser-foot shank 8 with foot-portion 9.

Depending from the bed-plate is the shuttle-race 10 in which is mounted the shuttle provided with the thread-case 11 and co-operating with the needle in the production of stitches, the shuttle being actuated by the rock-shaft 12 in a well known manner. The bed-plate 1 is provided with a throat-plate 13 formed with a needle-hole 14 and feed-apertures 15 through which latter passes the feed-dog 16 fixed upon the feed-bar 17 and shown herein provided with parallel rows of feed-points. The feed-bar 17 is pivotally supported at one end by 95 center screws 18 upon the feed-rocker 19 which is mounted on the feed rock-shaft 20, journaled upon the conical-pointed center screws 20*, while the opposite end of the feed-bar has a lateral slot 21 entered by a 100 roller-stud 22 upon a lateral arm 23 of the feed-lifting rock-shaft 24, journaled upon the conical pointed center screws 24*. The feed-actuating and feed-lifting rock-shafts are or may be actuated by any suitable 105 means.

The upper face of the bed-plate at its forward end is shown notched to receive the foot-piece 25 of a forwardly projecting bracket 26 extending across the forward end 110

of the bed-plate and provided with upwardly projecting perforated bearing-lugs 27. Mounted upon the said bearing lugs by means of aligned fulcrum-screws 28 is a 5 rocking frame 29 disposed transversely of the bed-plate and provided with a handle 30 for tilting the same in opposition to a spring 31 secured by means of a screw upon a countersunk seat provided therefor in the frame 26 and having its free end resting 10 against the under side of the handle 30.

Journaled in a suitable bearing aperture in the frame 29 is a substantially vertical stud 33 which is tapped into the hub 34 of 15 the rotary carrier-disk 35. The carrier disk is provided with groups or clusters of peripheral radially-disposed fastener-recesses 36 with intermediate tongues 37, the adjacent groups being separated by spacing 20 tongues 38 of greater width than those between the component recesses of each group.

Secured upon the rocking frame 29 adjacent the front bearing lug 27, by means 25 of the screws 39, is a bracket-plate 40 having an angular boss 41 open at the outer side to receive the lower end of the angular fastener chute or magazine tube 42 which is confined therein by means of clamp-plates 43 and fastening screws 44. The tube 30 42 has a longitudinal slot or opening upon its outer side and is shaped in cross-section to substantially fit the tabi-fastening plates or fasteners 45 which are formed in practice 35 adjacent their larger ends with a transverse row of apertures 46 to receive the stitches by which they are secured to the fabric. The chute is clamped in position with its lower extremity only sufficiently above the upper face of the carrier 35 to provide suitable 40 clearance for the free rotation of the latter, and the lower extremity or mouth of the chute is in register, at its inner end, or that nearest the journal-stud 33, with the inner ends of the fastener recesses 36 of the 45 carrier.

Secured to the under side of the rocking frame 29 by means of the screws 47 is a curved plate 48 having in its upper side a segmental recess 49 adapted to receive the 50 tabi-fasteners 45 in their passage from the mouth of the chute 42 to the needle-hole 14 of the throat-plate, the recess 49 being closed at the top by means of a segmental cap-plate 50, secured in position by screws 51, so as 55 to form a runway for the fasteners which embraces the outer marginal portion of the carrier disk 35 formed with the fastener recesses 36.

The delivery portion of the runway afforded by the overlapping plates 48 and 50 is notched above the throat-plate to expose 60 a portion of the feed-dog 16 and to form the spaced tongues 48^x and 50^x embracing the margin of the carrier 35 and overlying one side of the feed-dog, the tongue 48^x being

sufficiently narrow to expose a portion of the area of the serrated under sides 37^x of the spacing tongues 37 to the action of the feed-dog which they partially overlie. The cap-plate 50 is shown provided at its inner 70 edge opposite the stitching point with two indicator notches 52 coöperating with radial marks 53 opposite the centers of the divisional tongues 38 between the clusters of recesses 36.

Preparatory to operating the machine, the carrier is turned by hand to bring one of its marks or graduations 53 into register with one of the indicator marks 52, which are a stitch-length apart, whereby the carrier is brought into such relation with the needle-hole 14 of the throat-plate that the operation of the feed-dog upon the bottom of the carrier or the interposed fabric will propel the latter in such manner as to bring 80 the thread-apertures 46 of the fasteners 45 successively into register with the needle-hole, which apertures 46 are formed a stitch-length apart and the extreme apertures not more than a stitch-length from the adjacent 90 edge of the fastener.

To insure the proper presentation to the stitch-forming mechanism of the marginal portion of the two plies of fabric and the inner edges of the fasteners to be secured 95 between the same, an edge-guide is provided, consisting of the foot-plate 54 secured by means of fastening screws 55 upon the throat-plate and provided with an upturned guiding lip 56, which is in practice 100 set back from the needle-hole a space about equivalent to the distance between the apertures 46 and the inner edge of the fasteners 45, whereby the guide serves not only to direct the edges of the spaced upper and lower 105 plies of fabric, but to coöperate with the runway for the fasteners in guiding the latter to the stitching position.

As shown in Figs. 6 and 7, the operative portion 9 of the presser-foot is made comparatively narrow and is slightly curved to conform with the periphery of the carrier 35 and is provided midway of its length with the needle-hole 9^x.

In the use of the attachment above described, the chute or magazine 42 is first provided with a supply of fasteners 45, as represented in Fig. 1, and the carrier 35 rotated by hand in the direction of feed to bring one of its indicator marks 53 into 110 register with one of the marks 52 of the runway. The carrier-supporting frame 29 is then tilted, as represented in Fig. 1, by pressure upon the handle 30 for introduction of the lower ply *a* of material, after which the 115 upper ply *b* of material is introduced beneath the presser-foot above the carrier, and the presser-foot lowered. The machine 120 being set in motion, the needle makes its reciprocations through the two plies of fabric 125 130

in the production of a line of stitches *c* and the feed-dog, which acts upon the material interposed at one side between the same and the serrated lower face of the carrier tongue 5 37 and at the other side between itself and the bottom of the presser-foot 9, so as to advance the work for spacing the stitches and to propel the carrier 35. As the base or inner end portions of the fasteners are 10 guided past the stitching point by the step-by-step rotary motion of the carrier, they are stitched in between the overlapped plies of fabric, as represented in Fig. 8. After the parts of the article are united as described, the fabrics are reversely folded upon themselves into the form shown in Fig. 9, so as to bring their initial outer faces together and to thus conceal the line of stitching and to expose the tapered outer end portions of the fasteners. 15

As the edge-guide 56 is arranged parallel with the direction of the feed, and the fastener recesses 36 of the carrier 35 are open at the outer end, it will be observed that as the 20 fasteners continue their advance beyond the stitching point they will move in a straight path in the direction of feed of the material and will gradually be withdrawn from their respective recesses, and thus disengaged 25 from the carrier.

Having thus set forth the nature of the invention what I claim herein is:—

1. The combination with a straight-away stitching machine comprising stitch-forming mechanism including a reciprocating needle, feeding mechanism for imparting an advance movement to the work after each stitch-forming operation, and a throat-plate through which the needle reciprocates, of a 35 fastener chute, a rotary carrier formed with peripheral radially disposed fastener-recesses adapted to register successively with the mouth of said chute and the stitch-forming mechanism, and means for pressing said 40 carrier upon the throat-plate adjacent the stitch-forming mechanism, said feeding mechanism by its engagement with an interposed ply of fabric serving to propel the carrier to feed the fasteners to the stitch-forming mechanism for attachment to said fabric. 45

2. In a sewing machine, the combination with stitch-forming and work-feeding mechanisms, and a throat-plate, of a fastener chute, a rotary carrier formed with peripheral radially-disposed fastener recesses adapted to register successively with the mouth of said chute and the stitch-forming mechanism, a rocking supporting frame for 55 said chute and carrier, fixed fulcra for said frame parallel with the throat-plate and upon which said frame is adapted to tilt, a spring for pressing said carrier upon the throat-plate adjacent the stitch-forming mechanism, a presser-foot disposed above 60

the throat-plate and adjacent the periphery of said carrier, and a spring independent of that of said carrier for pressing said presser-foot upon the throat-plate.

3. In a sewing machine, the combination 70 with stitch-forming mechanism, a throat-plate and feeding-mechanism including a feed-dog having rising and falling movements through said throat-plate, of a fastener chute, a rotary carrier with its periphery partially overlying the feed-dog upon the side thereof nearest its axis of rotation and formed with radially arranged fastener recesses extending inwardly from the periphery and adapted to register successively with the mouth of said chute and the stitch-forming mechanism, means for pressing said carrier upon the throat-plate adjacent the stitch-forming mechanism, and a spring-actuated presser-foot disposed 75 above the throat-plate and overlying a portion of the feed-dog adjacent that covered by said carrier. 80

4. In a sewing machine, the combination 90 with stitch-forming mechanism, a throat-plate and feeding-mechanism including a feed-dog having rising and falling movements through said throat-plate and adapted to impart to the work an advance movement after each stitch-forming operation, of a 95 fastener chute, a rotary carrier with its periphery partially overlying the feed-dog upon the side thereof nearest its axis of rotation and formed with radially-arranged fastener recesses extending inwardly from the periphery and adapted to register successively with the mouth of said chute and the stitch-forming mechanism, said peripheral recesses being arranged in groups or clusters of which the component recesses are 100 equi-distantly spaced and the nearer recesses of adjacent groups or clusters are spaced apart a greater distance, and means for pressing said carrier upon the throat-plate and feed-dog whereby the feed-dog by its 105 engagement with an interposed ply of fabric serves to propel the carrier to feed the fasteners to the stitch-forming mechanism for attachment to said fabric. 110

5. In a sewing machine, the combination 115 with stitch-forming mechanism, a throat-plate and feeding mechanism including a feed-dog having rising and falling movements through said throat-plate, of a fastener chute, a rotary carrier with its periphery partially overlying the feed-dog upon the side thereof nearest its axis of rotation and formed with radially-arranged fastener recesses extending inwardly from the periphery and adapted to register successively 120 with the mouth of said chute and the stitch-forming mechanism, said rotary carrier having its peripheral recesses arranged in groups or clusters spaced apart in multiples 125 of stitch-lengths and being provided with 130

indicator marks corresponding with such spacing, a non-rotary supporting frame for said rotary carrier having an indicator mark adapted to register with those of the rotary carrier in determining its initial position relative to the stitch-forming mechanism, and a spring-actuated presser-foot disposed above the throat-plate and overlying a portion of the feed-dog adjacent that covered 10 by said carrier.

6. In a sewing machine, the combination with stitch-forming and work-feeding mechanisms, and a throat-plate, of a fastener chute, a rotary carrier formed with peripheral radially-disposed fastener recesses adapted to register successively with the mouth of said chute and the stitch-forming mechanism, a rotary supporting frame for said chute and carrier formed with a runway 15 extending from the mouth of said chute toward the stitch-forming mechanism and

embracing a portion of the periphery of said carrier, alined fulcra parallel with the throat-plate upon which said frame is mounted, a spring acting upon said frame 25 to press the rotary carrier upon the throat-plate, a spring-actuated presser-foot disposed above the throat-plate and adjacent the periphery of said carrier, and a stationary edge-guide adjacent the presser-foot and adapted to coöperate with said runway of the supporting frame in confining the fasteners within said peripheral recesses of the carrier in their approach to the stitch-forming mechanism.

In testimony whereof, I have signed my name to this specification, in the presence of two subscribing witnesses.

CHARLES M. HORTON.
